UNITED STATES PATENT OFFICE.

FRANK PORTER STONE, OF CHICAGO, ILLINOIS.

DESIGN FOR A BROUGHAM-BODY.

SPECIFICATION forming part of Design No. 22,855, dated October 24, 1893.

Application filed August 11, 1893. Serial No. 482,943. Term of patent 7 years.

To all whom it may concern:

Be it known that I, FRANK PORTER STONE, of Chicago, county of Cook, and State of Illinois, have produced a new and original Design for a Brougham-Body, of which the following is a specification, reference being had to the accompanying drawing.

In the accompanying drawing, I illustrate a side elevation.

10 The leading features of my design consists in the particular shape and ornamentation of the body as comprised in the body.

15 Referring to the figures on the drawing, 1 indicates the body, and 2 the belt line, which has the shape of a compound curve, as illustrated. The front and rear, indicated at 2 and 3, are curved toward each other. The window is arranged with a side molding 6, curved oppositely from the front of the carriage, and with a top molding 7 curved oppo-

sitely from that portion of the belt line opposite to it. The window is defined by curved moldings 8, and is provided with an oval glass 9. Below the belt line, in front, the coupé pillar is finished with a curve to correspond 25 with the front of the body above the belt line. The boot is distinguished by a lower curved line 9, and an upper curved line 10. The line 9 breaks abruptly into a line 11, which forms the bottom of the driver's platform. 30

What I claim is—

The design for a brougham body herein shown and described.

In testimony of all which I have hereunto subscribed my name.

FRANK PORTER STONE.
